UNITED STATES PATENT OFFICE.

OLAV ESKIL JORGENSEN, OF FOREST HILLS, NEW YORK, ASSIGNOR TO WORTHINGTON PUMP AND MACHINERY CORPORATION, OF NEW YORK, N. Y., A CORPORATION OF VIRGINIA.

INTERNAL-COMBUSTION ENGINE.

Application filed February 16, 1922. Serial No. 537,136.

The present invention relates to improvements in internal combustion engines, and particularly to engines of the Diesel type.

The object of the invention is to provide a durable and efficient double-acting engine of the two cycle Diesel type in a compact form particularly suitable for heavy power purposes, as, for example, for marine engines, the construction being such that the various parts of the engine may be readily disassembled and re-assembled.

With these general objects in view, the invention consists in the features, details of construction and combination of parts which will first be described in connection with the accompanying drawings and then particularly pointed out in the claims.

In the drawing,—

Fig. 1 is a vertical section, partly in elevation, on an enlarged scale through the center of an engine cylinder embodying certain features of my invention;

Fig. 2 is an enlarged sectional view of the piston with parts of the cylinder;

Fig. 3 is a horizontal section on the line 3—3 of Fig. 2;

Fig. 4 is a horizontal section on the line 4—4 of Fig. 2;

Fig. 5 is a horizontal section on the line 5—5 of Fig. 1;

Fig. 6 is a diagrammatic side elevation of the upper part of an engine comprising several engine units and a scavenging air pump embodying my invention;

Fig. 7 is a detail plan view of the valve mechanism at the upper end of the engine, shown in Fig. 1;

Fig. 8 is a horizontal section of the piston rod;

Fig. 9 is a diagrammatic transverse sectional view showing the scavenging air pump; and

Figs. 10 and 11 are enlarged sectional views showing the air pump.

Referring to the drawings, A, Fig. 6, indicates the frame of the engine, and B the cylinder base which is supported by the frame and is the sole means for supporting the upper and lower cylinders respectively of the engine. This cylinder base has channels, chambers or passages, some of which serve as the exhaust ports and others as the

inlet ports for the scavenging air. The cylinder base has a diaphragm, as indicated at b, Fig. 1, which separates the upper and lower sets of ports from each other.

The cylinders are each formed with an enlarged wall at one end, the upper cylinder having this enlargement at the lower end and the lower cylinder having the enlargement at the upper end. These enlarged portions are cylindrical and fit into corresponding openings in the cylinder base. In the best embodiment of the invention, each cylinder comprises a plurality of parts, in the present example two parts, an outer member 1 and an inner member or cylinder liner 2.

In the best embodiment of the invention the liner 2 extends beyond the corresponding outer member 1 at one end and the liner and its outer member are flanged, as shown at 3 and 4 respectively, to form the enlarged diameter of the cylinder.

Each liner has its enlarged end inserted in a corresponding recess in the diaphragm and is provided on one side with inlet ports for scavenging air, as indicated at 5, and on the other side with exhaust ports 6. Each cylinder is held to the cylinder base by suitable means. In the best embodiment of the invention, the clamping means comprises a clamping ring, as indicated at D, D', secured to the cylinder base by stud bolts 7 and nuts 8. Each clamping ring has one inner edge coned or chamfered to bear against the corresponding coned or chamfered edge of the flange of the respective outer member 1. By removing the nuts 8, the cylinder is released and may be removed from the cylinder base. When in place it is held tightly to the cylinder base by the clamping ring and nuts.

The cylinders are provided with water jackets, indicated at C, C', respectively. Each jacket has one end arranged to enter a counterbore in the clamping ring and to make a water-tight joint therewith. To insure this under all conditions, a packing ring may be inserted between the end of the jacket and the clamping ring, as indicated at 9. The packing ring may be inserted in a counterbore in the end of the jacket, as will be clear from Fig. 1. The jacket is held in

place by suitable means. In the best embodiment of the invention, the jacket is held in place by its cylinder, only, so that when the cylinder is released from the cylinder 5 base, the cylinder and its water jacket may be removed as a unit. In order to accomplish this result, the cylinder has a screw threaded boss to which is screwed a thimble 10, 11 having an outwardly extending 10 flange counterbored at the corner, as shown in Fig. 1, and the jacket has an inward extending flange arranged to enter the counterbore. Suitable stud-bolts and nuts serve to 15 secure the jacket to the thimble.

15 The thimble 10 for the upper cylinder is arranged to receive a cylindrical block 12 carrying suitable poppet valve mechanism hereinafter more fully described. The thimble 11 for the lower cylinder, serves as 20 the packing-chamber to receive the piston-rod packing, not shown. This packing, when in place, may be tightened by a stuffing box gland 13 held in place by bolts 13' which extend through the flange of the water 25 jacket and are screwed into the flange of the lower thimble.

The lower jacket E', Fig. 6, is provided with a boss 14 to receive a circular block 15 which carries the valve device for supplying 30 fuel to the lower cylinder. The circular block 15 has a cylindrical projection 16 which fits into a recess in a boss 17 formed on the lower cylinder.

In the best embodiment of the invention 35 the ends of the cylinders are of a novel construction which gives great strength with relatively light weight. In this construction, the cylinder end where the thimble 10 or 11 is screwed to it, is made thick enough 40 to form a substantial ring of metal which will successfully resist any stresses to which it may be subjected. The wall of the cylinder end from the ring toward the cylindrical portion constituting the main body of the 45 cylinder, comprises two zones, viz, a conical zone and a spherical zone, the latter being next to the cylinder body, while the conical zone joins the spherical zone to the ring. In the best embodiment of the invention the 50 conical portion is tangential to the spherical portion, and while in practice a small deviation from this ideal is not a serious objection, the more nearly the approach to the ideal condition, the lighter the wall may be 55 for the same strength.

While the piston may be of any suitable construction, the present invention includes a new type of piston particularly coacting with the cylinder. This piston has one end 60 domed as indicated at 18, Figs. 1 and 2, to enter the corresponding end of the cylinder and nearly but not quite fill the space therein, only a small amount of clearance being 65 left therein, say, for example, from about 5 to 7 per cent. The crank end 19 of the pis-

ton must be of such exterior configuration as to reduce the final or minimum clearance to a relative amount suitable in engines of this type, while locating it so that the fuel valves may discharge into it at the proper 70 time. This is accomplished in the present example by forming this end of the piston so that its portion next to the piston-rod is substantially cylindrical in cross-section, 75 while the intermediate portion is substantially elliptical in cross-section, as shown in Fig. 4. In this way a space is left on each side of the piston opposite the fuel injection nozzles. From this elliptical portion the piston-end 19 flares outward to the full 80 diameter of the piston body.

In the best embodiment of the invention, the piston and piston rod are specially constructed to provide a durable, readily assembled device. The piston-rod 20 is 85 formed with an enlarged end 21 having a flange 22, while near the other end of the piston the rod has an intermediate flange 23 below which is an enlargement 24 providing 90 a shoulder.

The piston-wall comprises two cylindrical body portions, 25 and 26, each provided with a series of grooves for the packing rings 27.

These two cylindrical portions have their 95 adjacent ends somewhat reduced in diameter, the reduced portions being received within the corresponding circular portions or rings of an intermediate split ring member 28 formed of three sections joined by bolts and nuts passing through radially extending flanges 29 formed on flat webs 30, extending like chords of the circumference of the piston, as will be clear from Fig. 3.

The intermediate member is locked to the lower cylindrical portion 26 of the piston 100 wall, in any suitable way, as, for example, by providing the intermediate split-ring member with an inward extending circumferential rib 31 extending into a circumferential groove in the outer surface of the lower cylindrical portion, as will be clear 105 from Fig. 2. The upper cylindrical portion 25 is not locked to the intermediate portion but is left free to expand and contract, the joint between the two being, however, a 110 water tight sliding connection. The upper cylindrical body portion 25 is provided below its upper end with an inward extending flange 32 which rests on the flange 22 at the upper end of the piston-rod, and against 115 which rests the upper dome-shaped piston end 18, suitable machine screws 33 holding the parts together, as shown in Fig. 2. The lower cylindrical body portion 26 is provided with an inward extending flange 34 120 making a tight fit with the outer surface of the intermediate flange 23 of the piston rod. The lower piston end 19 fits against the lower surface of said flange 34 and is held 125 to the flange by machine screws 35. Suit-

able long machine screws 36 pass through the intermediate flange 23 and are threaded into the lower piston end portion 19.

In an engine of this type it is important 5 to provide water circulation for cooling the piston heads or end portions and this may be done, as shown in Fig. 2, by making the piston rod 20 hollow or tubular and inserting within it a water pipe, as indicated at 37, 10 whose exterior diameter is less than the interior diameter of the rod, so as to leave an annular water space around the pipe. To the pipe 37 is secured a collar 38 forming a baffle or diaphragm. The piston rod has 15 water passages, above and below the collar 38, as indicated at 39 and 40, these connecting the space inside the lower piston end 19 with the annular space of the piston rod. The water pipe 37 has a collar 41 secured to 20 it near its upper end, this collar being provided with holes 42 for the passage of water. A bushing 43 threaded into the piston rod is provided with an inturned flange which laps over the collar 41. While the water may 25 flow up through the water pipe and thence down through the annular passage, it will be advantageous to allow the cooling water to flow up the annular passage and thence down and out through the water pipe, because in this way the coldest water will be 30 next to the piston rod. The water may be admitted to the moving piston-rod, and discharged therefrom in any suitable way, as, for example, by any of the means already 35 well known in the art.

In order to assist in maintaining a water tight joint at the circumference of the intermediate flange 23, the piston-rod periphery of this flange is provided with a 40 groove into which may be cast a suitable alloy through a notch provided for that purpose. The alloy in the groove is indicated at 44, Fig. 2, and the notch, also filled with alloy, is indicated at 45.

45 The collars 38 and 41 are secured to the water pipe 37 by electric welding, as is indicated by the solid block in Fig. 2.

It will be obvious that by the construction 50 of the piston as described, a light yet strong piston is produced, which may be readily assembled and disassembled. Also, the longitudinal expansion and contraction of the piston due to temperature changes is provided for.

55 The valve mechanism at the upper end of the cylinder comprises an air-starting valve and a fuel valve, with valve operating devices by which, at starting, the air valve may be operated with proper timing, and so soon as the engine is operating properly the air-starting valve may be cut out of operating and the fuel valve put in action.

The air-starting valve is an ordinary poppet valve, opening inward, as indicated at 46, Fig. 1. It is yieldingly held shut by a

spring 47 and its spindle projects outward as indicated at 48. To the upper end of the water jacket is secured a post 49 in which is fulcrumed a rocker-arm 50 arranged to be oscillated by a rod 51 from any suitable moving part of the engine, not shown. The rocker-arm 50 carries a fulcrum 52 at its free end on which is journaled an adjustable trip-arm 53 having one end provided with a screw 54 which, under certain conditions, 70 will strike the free end of the starting-air valve spindle 48 and thus force the valve open. The other end of the trip-arm 53 is pivotally connected to the end of an eccentric rod 55 arranged to be adjusted by an eccentric 56 fixed on an eccentric shaft 57. This eccentric shaft is provided with a handle 57', shown in Fig. 7, by which its eccentric may be rotated to adjust it. The pivot which connects the trip arm to its eccentric rod has its axis coincident with the axis of the fulcrum of the rocker-arm 50 when the corresponding eccentric is in such a position as to hold the trip-arm out of engagement with the starting air-valve. 90

The fuel valve 58 is also of the poppet type normally closed by a spring 59 and having its spindle arranged to be struck by the end of a screw 60 carried by the trip-arm 53. When the trip-arm is out of action 95 on the starting air-valve 46, it is in action on the fuel valve, and vice-versa, this being determined by the position of the eccentric 56.

With a plurality of engine-units, one or 100 more cylinders may be supplied with starting air to start all the engines, the other cylinders receiving fuel at the proper time. As soon as the engines are turning under the pressure of the combustion gases in some cylinders, the eccentric or eccentrics 56 may be turned over so as to shift the trip-arm or trip-arms and cut out the starting-air mechanism, thereby cutting in the fuel valves for 105 those cylinders. 110

The lower cylinders are not arranged for the use of starting-air but have only fuel valves of the poppet-valve type, as shown at 61, each being operated by a rocker 62 secured on a rocker arm 63 oscillated by a rod 64 from a moving part of the engine, not shown. The poppet-valve is held closed by a spring 65. 115

The fuel valves illustrated for the upper and lower cylinders are of any suitable type 120 in which the oil is blown in by injection air. As valves of this type are well known no specific description of the same is required.

An important feature of the power plant here set forth comprises an improved arrangement of a plurality of double-acting engines of the Diesel type on a cylinder base in the manner described, with a scavenging air pump. Such an arrangement is shown in Fig. 6 in which E, E' are the air-pump cyl- 125 130

inders. The general arrangement of the air-pump will be clear from Figs. 9, 10 and 11, the air pump being shown as of the type described and claimed in my Letters Patent No. 1,447,514, dated March 6, 1923.

Referring to Fig. 11, E is the cylinder of the upper air-pump, and E₁ the cylinder of the lower air-pump. F is the upper piston, F₁ the lower piston, and G the piston rod connected to both pistons. H is the upper cylinder head, H₁ the lower cylinder head and H₂ an intermediate head common to both cylinders.

The intermediate head H₂ is flanged and is fitted into a seat formed in a septum or horizontal partition *a*, Fig. 10, which constitutes a part of the cylinder base B, the partition *a* having a horizontal flange *a*₁ and a vertical annular flange *a*₂ at the seat. The intermediate head H₂ is secured in its seat in any suitable way as, for example, by machine screws 1 which are accessible from the upper side of the cylinder base when the upper air pump is removed.

The upper cylinder E is provided with a supporting member having a cylindrical hub-portion *e*, Fig. 10, arranged to enter a corresponding hole in the upper member or plate *a*₃ of the cylinder base and having a flange *e*₁, overhanging said plate *a*₃, to which it may be secured in any suitable way, as, for example, by machine screws, as indicated at *x*, Fig. 11. The cylinder E is of such length that its lower end reaches nearly but not quite to the upper surface of the intermediate head H₂, whereby a suitable passage or port for the entrance and discharge of air beneath the upper piston F is provided all around the cylinder, this opening leading into an upper chamber or space I formed in the cylinder base above the septum *a*. The lower cylinder is similarly constructed and mounted in the cylinder base, being inserted into the cylinder base from below upward and held in place by the machine screws 3. Its upper edge extends nearly but not quite to the lower surface of the intermediate head H₂ so as to leave an air passage or port all around the cylinder whereby the space in the lower cylinder above the piston F₁ is put in communication with a lower chamber or space I₁, Fig. 10, formed in the cylinder base below the septum *a*.

The side walls of the cylinder base are provided with openings leading from the upper and lower chambers I, I₁, respectively, to a suction valve chest K, and corresponding openings leading to a discharge valve chest K₁. These valve chests are secured to opposite sides of the cylinder base and each has two sets of valves. The sets of suction valves are indicated at L₁, L₂ and the sets of discharge valves at M₁, M₂ respectively. While any suitable valves may be employed, those indicated are of the plate spring va-

riety, for example, such as are fully disclosed in Patent No. 1,341,145, dated May 25, 1920.

The upper end of the cylinder E is connected by a suitable passage N with the chamber I₁ below the diaphragm *a*, the passage N opening into the top of the cylinder, as will be clear from Fig. 11. The lower end of the cylinder E₁ is connected, by a passage N₁, with the chamber I above the diaphragm *a*, the passage N₁ opening into the bottom of the cylinder E₁, as will be understood from Fig. 11. Each passage N or N₁ is formed partly in its own cylinder, and partly in the cylinder base B, as shown in Fig. 11. The part of each passage within the cylinder base is enclosed by a wall *n*.

The piston rod G is reciprocated in any suitable way from the main shaft D, as, for example, through a crank O, connecting rod P, and cross-head Q running in guides R.

By this combination a large yet short conduit S may be carried closely alongside the cylinder base to supply scavenging air to each engine in its turn, the engines of course having their cranks set at angles to one another so that the working strokes of the engines will occur in the desired timed relation.

By this arrangement of the engines and the scavenging air-pumps, any engine or the air-pump may be dismantled more readily than has heretofore been possible and with the removal of a minimum of parts, but, also, there is less loss by friction in the flow of air to the engines from the pump and hence a greater relative efficiency.

While in the foregoing specification, the invention has been more particularly shown and described as embodied in a vertical engine, it is to be understood that the invention is applicable to horizontal or inclined engines, and that the terms "upper" and "lower" referring to the cylinders, are to be understood as including cylinders which are not above and below each other, but nearest to or farthest from the crank shaft.

What is claimed is:

1. In an internal combustion engine, the combination, with a cylinder base having a vertical bore and having scavenging air inlet passages and exhaust passages, of a crank shaft, a cylinder projecting into the said vertical bore and provided with inlet and exhaust ports in communication with the corresponding passages of the cylinder base, said cylinder being detachably secured to the cylinder base on the side away from the crank shaft and having its combustion chamber portion above the cylinder base, a piston movable in the cylinder, and means for driving the crank shaft from said piston.

2. In an internal combustion engine, the combination, with a cylinder base having a vertical bore and inlet and exhaust passages,

- of a crank shaft, a cylinder detachably secured to the cylinder base on the side away from the crank shaft, said cylinder comprising an outer member and a liner, the latter extending beyond the outer member and having inlet and exhaust ports communicating with the corresponding inlet and exhaust passages of the cylinder base, a piston movable in the cylinder, and means for driving the crank-shaft from the engine.
3. In an internal combustion engine, the combination, with a cylinder base having a vertical bore, and having scavenging air inlet passages and exhaust passages, of a crank shaft, a cylinder projecting into the said vertical bore and provided with inlet and exhaust ports in communication with the corresponding passages of the cylinder base, said cylinder being detachably secured to the cylinder base on the side away from the crank shaft and having its combustion chamber portion above the cylinder base, a water-jacket for said cylinder, said water-jacket being fastened only to the outer end of the cylinder, whereby upon removal of the cylinder from the cylinder-base its water jacket also is removed with it, and a piston arranged to work in both cylinders.
- 13 4. In an internal combustion engine, the combination, with a cylinder base having a vertical bore and having scavenging air inlet passages and exhaust passages, of a pair of cylinders projecting into the said vertical bore from opposite sides of the cylinder base, each cylinder being provided with inlet and exhaust ports in communication with the corresponding passages of the cylinder base, said cylinders being detachably secured to the cylinder base, one cylinder having its combustion chamber portion above the cylinder base and the other having its combustion chamber portion below the cylinder base, and a piston arranged to work in both cylinders.
- 23 5. In an internal combustion engine, the combination, with a cylinder base having a vertical bore, and having scavenging air inlet passages and exhaust passages, of a pair of cylinders projecting into the said vertical bore from opposite sides of the cylinder base, each cylinder comprising an outer member and a liner, the latter extending beyond the outer member and having inlet and exhaust ports in communication with the corresponding passages of the cylinder base, said cylinders being detachably secured to the cylinder base, one cylinder having its combustion chamber portion above the cylinder base and the other having its combustion chamber portion below the cylinder base, and a piston arranged to work in both cylinders.
- 33 6. In an internal combustion engine, the combination, with a cylinder base having a vertical bore and having an intermediate diaphragm provided with an opening, of a pair of cylinders arranged on opposite sides of the cylinder base, each cylinder having an end portion projecting into the vertical bore and contacting with the diaphragm, a clamping ring for each cylinder, said rings being arranged on opposite sides of the cylinder base, and means for detachably securing each clamping ring to the cylinder base to hold its respective cylinder in place.
- 43 7. In an internal combustion engine, the combination, with a cylinder base having a vertical bore and having an intermediate diaphragm provided with an opening, of a pair of cylinders arranged on opposite sides of the cylinder base, each cylinder having an end portion projecting into the vertical bore and contacting with the diaphragm, a clamping ring for each cylinder, said rings being arranged on opposite sides of the cylinder base, and means for detachably securing each clamping ring to the cylinder base to hold its respective cylinder in place.
- 53 8. In an internal combustion engine, the combination, with a cylinder base having a vertical bore and having an intermediate diaphragm provided with an opening, of a pair of cylinders arranged on opposite sides of the cylinder base, each cylinder having an end portion projecting into the vertical bore and contacting with the diaphragm, a clamping ring for each cylinder, said rings being arranged on opposite sides of the cylinder base, means for detachably securing each clamping ring to the cylinder base to hold its respective cylinder in place, and a water jacket for each cylinder, each jacket being detachably secured only to the outer end of its respective cylinder and being arranged to have a slideable water-tight connection with its respective clamping ring.
- 63 9. In an internal combustion engine, the combination, with a cylinder base having a vertical bore and a diaphragm provided with an opening, a pair of cylinders arranged on opposite sides of the cylinder base, each having an end projecting into the vertical bore and making contact with the diaphragm, a clamping ring for each cylinder, said rings being arranged on opposite sides of the cylinder base, each ring having a counter-bore in its outer face, and means for detachably securing each ring to the cylinder base to hold the cylinders in place, of a water jacket for each cylinder, each jacket

having one end arranged to enter the counter bore of the corresponding clamping ring, and means for detachably connecting each water jacket to the outer end of its respective cylinder.

10. In an internal combustion engine, a cylinder having a dome-like end provided with only one opening, which is circular and centrally arranged, the wall of the cylinder 10 being thickened around said opening to form a ring, the wall of the dome comprising two zones, that zone next to the cylindrical body portion of the cylinder being the zone of a sphere and the remainder of the dome being 15 a conoidal zone tangent to the spherical portion and connecting it with the ring, substantially as described.

11. In a double acting internal combustion engine, the combination, with a pair of 20 cylinders, each having a dome-like end provided with a central opening, the wall of each end being thickened around the opening to form a ring, each dome-like end comprising the zone of a sphere next to the 25 cylindrical body portion of the cylinder and a conoidal zone tangent to the spherical zone and connecting it with the corresponding ring portion, of a piston working in both cylinders, a piston-rod connected to the piston- 30 ton and passing through the central opening of one end, a stuffing box secured to the ring around said central opening for packing the piston-rod, and a plug inserted in the central opening of the other cylinder, 35 and provided with valve mechanism for the admission of fuel to its cylinder, substantially as described.

12. In a double-acting internal combustion engine, the combination, with a pair of cylinders, each having a dome-like end provided with a central opening, the wall of each end being thickened around the opening to form a ring, each dome-like end comprising the zone of a sphere next to the 45 cylindrical body portion of the cylinder and a conoidal zone tangent to the spherical zone and connecting it with the corresponding ring portion, of a piston working in both cylinders, a piston-rod connected to the piston- 50 ton and passing through the central opening of one end, a stuffing box secured to the ring around said central opening for packing the piston-rod, a plug inserted in the central opening of the other cylinder and 55 provided with valve mechanism for the admission of fuel to its cylinder, and a fuel valve mechanism for admission of fuel to

the cylinder having the stuffing box, said fuel valve mechanism being arranged in 60 the conoidal zone portion.

13. In an internal combustion engine, the combination, with a cylinder having an outwardly domed end provided with a central opening, a piston rod passing through said opening, and a packing gland arranged to pack the opening, of a piston secured to the rod and having an end arranged to enter the domed end of the cylinder, said end being shaped to form a clearance space in said domed end separated from and closed to the 70 packing gland to protect the packing gland from the combustion, and means secured to the domed end of the cylinder for injecting fuel into said clearance space.

14. In an internal combustion engine, the 75 combination, with a cylinder having a domed end provided with a central opening, a piston rod passing through said opening, and a packing gland arranged to pack the opening, of a piston secured to the rod and having an end arranged to enter the domed end of the cylinder, said end being circular in cross section near the piston rod and near the cylindrical body portion of the piston and elliptical in cross section at its intermediate portion, whereby a clearance space is formed between this elliptical portion and the domed end of the cylinder, and means for injecting fuel into said clearance space.

15. In an internal combustion engine, the 80 combination, with a cylinder base, a frame for supporting the same, a plurality of engine units, each comprising a pair of cylinders detachably connected to opposite sides of the cylinder base in line with each other, 85 said cylinders having scavenging air ports within the cylinder base, a piston for each engine unit working in both of its cylinders, a piston-rod for each piston, a main crank-shaft, and connections between each piston-rod and the crank-shaft whereby the shaft is 90 rotated, of a double-acting scavenging air-pump comprising two cylinders secured on opposite sides of the cylinder base in line with each other and having the air outlets 95 of the two cylinders on the same side of the cylinders, and an air conduit connected to 100 said air outlet extending along the cylinder base and connecting to the scavenging air 105 ports of each engine cylinder.

In testimony whereof, I have hereunto set my hand.

OLAV ESKIL JORGENSEN.
